UNITED STATES PATENT OFFICE

2,536,177

SIGNAL FLARE

George T. Harkins, Wichita, Kans., assignor to
 Miro-Flex Company, Inc., a corporation of
 Kansas

Application March 9, 1949, Serial No. 80,488

4 Claims. (Cl. 248—121)

1

This invention relates to portable reflecting signal flares of the type used on highways by motorists in emergencies. The flares have reflecting lenses which are visible at long distances when properly placed.

The primary object of the present invention is to provide an improved supporting base for the lens frame which forms a protective housing when in closed position and a strong support for holding the lenses in proper upright position when opened into extended position.

Another object of the invention is to provide an improved supporting base in which one or both of the closure members is divided longitudinally, so that the parts may form legs which may be spread and form a wider base for the unit.

Another object of the invention is to provide improved pivotal connections between the closure members and the lens-supporting frame. Also, rubber pads are used which afford inside cushions to prevent rattling and scratching of the lenses when the device is in closed position, and to provide outside friction grips for the supporting base when it is in extended position.

The invention is illustrated in a preferred embodiment in the accompanying drawings, in which—

Figure 1 is a plan view of the device in closed position; Fig. 2, a side elevational view of the same; Fig. 3, a vertical sectional view of the device in extended position; Fig. 4, a fragmentary sectional view, taken as indicated at line 4—4 of Fig. 3; Fig. 5, a fragmentary sectional view, taken as indicated at line 5—5 of Fig. 4; Fig. 6, a plan view of the device in extended position; Fig. 7, a vertical sectional view, taken as indicated at line 7—7 of Fig. 6; Fig. 8, a fragmentary sectional view, taken as indicated at line 8—8 of Fig. 6; and Fig. 9, a fragmentary sectional view, taken as indicated at line 9—9 of Fig. 6.

In the embodiment illustrated, an upwardly extending frame 10 is formed by a metal channel which extends around the edges of four reflecting lenses 11 which are arranged back to back. The frame is gripped together at its center by a nut and bolt 12 on which is provided a U-shaped perforate bracket 13, to hold the staff of a signal flag when the device is used in daylight. The frame 10 is mounted on a hinge-base member 13 which is in the form of an open-bottom box having a pair of top openings 14 through which the ends of the frame 10 extend. The end portions of the frame 10, and also the member 13, are impaled by a shaft 15 which may be in the form of a long rivet.

2 A pair of tray-shaped closure members 16 and 17 are pivotally connected to each other by means of upwardly extending ears 18 which are also impaled by the rivet 15. Preferably, the contacting faces of the ears are serrated to increase their yielding frictional resistance to turning. The edges of the closure members are in the form of stepped flanges 19 which are brought into abutting relationship and fit around the lens frame when the device is closed. The faces of the closure members are provided with U-shaped slots which are filled with short lengths of rubber hose 20 which provide inside cushions for the lens frame when in closed position, and outside friction grips when the device is in extended positions, as shown in Figs. 3 and 6. The pads are particularly useful in preventing slipping when the device is placed on an icy surface and subjected to considerable wind pressure.

20 The closure member 17 has a head portion 21 which is pivotally connected by its ears 18 to the rivet 15. It also has two complementary parts 22 which extend under an offset portion 23 of the head member 21 and are pivotally connected to the head member by means of rivets 24. The header member is also provided with slots 25 which are engaged by loose rivets 26 which limit the spreading movement of the legs, as shown by the dotted lines in Fig. 6. It will be understood that the closure member 16 may be constructed in the same manner as the divided closure member 17, if desired, but it has been found in practice that one set of spreadable legs to increase the width of the supporting base is generally sufficient.

30 As best shown in Figs. 1 and 4, a portion of each of the closure members 16 and 17 is struck upwardly at 27, to form an upwardly extending stop or abutment 28, to engage the lower portion of the hinge-base 13 and hold the lens frame in vertical position when the device is opened into extended position, as shown in Fig. 3. In using the device, it is merely necessary to swing the closure members from closed position, shown in Fig. 2, to extended position, shown in Fig. 3, and turn the leg members 22 outwardly, as indicated by the dotted position in Fig. 6. The device is then placed on the ground with the lenses arranged at right angles to the direction in which the signal is to be given. The device may be closed up by reversing these movements.

40 The foregoing detailed description is given for clearness of understanding only, and no unnecessary limitations should be understood there-

from, for some modifications will be obvious to those skilled in the art.

I claim:

1. A signal flare comprising: an upwardly extending frame for reflecting lenses having a hinge-base; and a pair of tray-shaped closure members pivotally connected at one end to said hinge-base and to each other to form a housing for said frame when turned together and a supporting base for the frame when opened into extended position, one of said closure members being divided longitudinally into two parts which are pivotally connected for spreading movement from each other so that the width of the supporting base may be extended.

2. A device as specified in claim 1, in which the closure members are each provided with a pair of upwardly extending ears having serrated contacting faces presented towards the ears of the companion closure member, and a rivet forms a shaft which impales said ears and hinge-base to form the pivotal connection between the three members.

3. A device as specified in claim 1, in which the divided closure member has a head portion which is pivotally connected to the hinge-base and com-

panion closure member, the divided two parts form legs which are pivotally connected to said head portion, and said legs each have a pin-and-slot connection with the head portion to limit their spreading movement from each other.

4. A device as specified in claim 1, in which the closure members are each provided with rubber-like pads which extend through said members and form inside cushions for the lens frame when in closed position and outside friction grips for the supporting base when in extended position.

GEORGE T. HARKINS.
